UNITED STATES PATENT OFFICE

FRED S. CALDWELL, OF DENVER, COLORADO

APPARATUS FOR MINING COAL

Application filed June 6, 1929. Serial No. 368,908.

My invention relates to apparatus for mining coal and its primary object is to provide a simple, highly practical and efficient apparatus for mining coal without the use of explosives or complicated machinery.

A further object is to provide apparatus for producing a disruptive and dislodging action upon a coal formation through the medium of a mechanically effected expansive movement.

An embodiment of my invention has been illustrated in the accompanying drawings which show my improved mechanism for attaining the above objects.

It is to be understood that the mechanism as shown may be varied in the construction and arrangement of its parts without departing from the scope of the invention.

In the drawings,

Figure 1 represents a sectional elevation of the mechanism in its operative position in a bore of a coal formation, before its operation.

Figure 2, a similar view of the apparatus after the coal at a side of the bore has been disrupted and dislodged by the expansive action produced in the operation of the apparatus.

Figure 3, a fragmentary elevation of the machine in the condition illustrated in Figure 2, showing a modified construction of one of the elements thereof, and

Figure 4, a face view of the breast of the coal formation showing at A a section along the line A—A, Figure 1 and at B a section on the line B—B, Figure 2.

Figures 5 and 6 are perspective views of the units comprised in the expansion element of the apparatus,

Figure 7 is a section along the line 7—7 of Figure 2 or the line 7—7 of Figure 3, and

Figure 8, a section taken on the line 8—8, Figure 3.

Similar characters of reference designate corresponding parts throughout the views.

The coal deposit to be mined has been indicated at 5. The first step of mining the coal by my improved method and apparatus consists in the production of holes 6 by the use of a suitable boring mechanism, similar to the present method of coal mining by means of explosives.

The holes are bored at a suitable distance from an under-cut 7 produced by a cutting machine as is usual in mining coal, and it is the part 8 between the holes and the undercut that is disrupted and removed in the operation of the invention.

The expansive element comprised in the mechanism for carrying the method involved in the invention, into effect, consists of a series of units capable of conjoint action upon the surface of the hole in which the element is inserted by a wedging motion imparted to the series by a power element exteriorly of the hole.

The units consist of plates 9 provided with oblong openings 10 and strung together on a flat-sided rod 12. The rod, which is preferably square as shown in the drawings, has at one end a head 13 against which the series of plates abut and its opposite end is in rigid connection with a piston-cylinder 14 slidably supported on a base 15.

The series of plates, at the end thereof opposite to that abutting against the head of the rod, is engaged by a hollow stem 16 of a piston 17 that is fitted for reciprocation in the cylinder 14.

The rod 12 is loosely fitted within the hollow stem to permit of free sliding movement of the piston and the cylinder in opposite directions.

A valve-controlled conduit 18 connected with the cylinder adjacent the closed end 19 thereof, provides for the admission of a motive fluid in the space 20 between the end of the sliding cylinder and the piston.

The flat-sided rod 12 fits loosely in the openings of the plates to permit of a non-

rotating motion of the latter along the rod. The plates are in this movement guided by bars 21 inserted in the hole 6 at opposite ends of the series of plates.

5 All or part of the plates are grooved at their ends, as best shown in Figure 5, to fit upon the guide bars and the latter have at their outer ends, heads or flanges 22 that abut upon the face of the coal formation.

10 The piston-stem 16 is rabbeted as at 23, to likewise fit upon the guide bars which thereby hold the piston against rotary motion in the cylinder.

15 In the construction illustrated in Figures 1 and 2, the end plates 9a of the series of units are heavier than the others, and all of the units are grooved at their ends to admit the guide bars.

20 In the form of the invention shown in Figure 3, heavier units 9a are placed at intervals between the other units of the series, and only the heavier units are grooved at their ends to fit upon the guide bars. The other lighter units are shorter, their length being substantially equal to the distance between the grooves of the heavier units as best shown in Figure 6.

25 The guide bars 21 are made of resilient material so that they may give during the expansive action of the element as will be further explained.

30 In the operation of the apparatus the guide bars together with the series of plates strung on the rod between the head of the same and the end of the hollow piston stem, are inserted in one of the holes of the coal formation, the plates being in a position oblique with relation to the longitudinal extent of the rod.

35 It is an essential feature of the mechanism that the length of the plates, i. e., the distance between their ends engaged by the opposed and parallel guide bars, exceeds the diameter of the hole, so that under ordinary conditions, the plates must naturally assume a slanting position in order to enter the hole.

40 By the admission of a motive fluid, such as compressed air, between the cylinder-end and the piston, the cylinder and the piston are forced to move in opposite directions with the result that the head at the end of the rod is moved outwardly toward the open end of the hole, and the end of the hollow piston stem is simultaneously moved farther into the hole.

45 It has been heretofore explained that the head and the sleeve engage the series of plates at opposite ends thereof and it will be readily apparent that the two forces acting in opposite directions upon the series, will tend to lessen the angle of inclination of the plates until they are placed at substantially right angles to the rod and to the direction in which the forces are applied to the series.

55 Inasmuch as the plates exceed in length the

diameter of the hole, it follows that an expansive and wedging action is exerted upon the wall of the hole and this action if continued will break and disrupt the coal deposit at the point of least resistance, i. e., at 70 the point directly opposite to the undercut.

The coal between the hole and the undercut is thus broken away and the operation is repeated in the other holes until the entire wall between the row of holes and the under-cut has been removed. Another row of holes is then bored above the space from which the coal has been removed, and the coal between these holes and the space dislodged in similar operations, and it will be 80 seen that in this manner an entire coal deposit is readily mined without the use of explosives or complicated machinery.

In the place of the cylinder and piston shown and described, the opposing forces upon the expansive element may be produced by other means and at any desired intensity through the intermediary of suitable gearing.

85 It is further to be understood that the force for the operation of the expansive element which in the embodiment of the invention herein disclosed, is applied at opposite ends thereof, may be applied at one end only by providing a fixed abutment for the opposite end. It is thought that this modification is too obvious to require further illustration.

90 The expansive element may be of any desired character or construction, the series of contacting and angularly moving plates being preferred not only by reason of its simplicity and efficient operation, but also because it provides for the engagement of the wall of the bore uniformly at every point thereof.

95 Any method to effect the angular movement of the plates from a slanting position to an erect position may be resorted to within the scope of the invention and as stated before, the effective forces may be applied at either end or at both ends of the series of plates by any suitable means.

100 The plates while being moved through an angle are simultaneously moving bodily lengthwise of the bore and this is another distinctive feature of the invention.

110 What I claim and desire to secure by Letters Patent is:

1. Apparatus for mining coal, comprising a rod, a series of units capable of moving through an angle on the rod and longitudinally relative to the same, and means to effect said movement of the units.

115 2. Apparatus for mining coal, comprising a headed member, a series of units engaging the head of the member and capable of moving through an angle on the member and longitudinally relative to the same, a movable member engaging the series at its end opposite to that engaged by the head, and

means to effect said movement of the units by movement of the members in opposite directions.

3. Apparatus for mining coal, comprising a rod, a series of loose plates adapted to move from a slanting position on the rod to a position at substantially right angles to the same, and means to effect said movement of the units by longitudinal movement of the rod.
- 10 4. Apparatus for mining coal, comprising a rod, a series of loose plates adapted to move lengthwise of the rod from a slanting position to a position at substantially right angles to the same, and means to effect said movement of the units.

15 5. Apparatus for mining coal, comprising a rod, a series of loose plates adapted to move from a slanting position on the rod to a position at substantially right angles to the same, loose guide bars guiding the plates in their said movement, and means to effect said movement.

20 6. Apparatus for mining coal, comprising a headed rod, a series of plates adapted to move from a slanting position on the rod to a position at substantially right angles to the same, laterally resilient guide bars guiding the plates in their said movement, and means to effect said movement.

25 30 7. Apparatus for mining coal, comprising a rod, a series of grooved plates adapted to move from a slanting position in a bore to a position at substantially right angles to the axis of the same, guide bars engaging in the grooves of the plates to guide the latter in their said movement, and means to effect said movement.

35 40 8. Apparatus for mining coal, comprising a headed rod, a series of plates adapted to move from a slanting position on the rod to a position at substantially right angles to the same, in engagement with the head of the rod, a member engaging the series at the end thereof opposite to that engaging the head, and means for moving the rod and the member simultaneously in opposite directions.

45 50 9. Apparatus for mining coal, comprising a headed rod, a series of plates adapted to move from a slanting position on the rod to a position at substantially right angles to the same, in engagement with the head of the rod, a sliding cylinder connected with the rod and having a closed end, a piston in the cylinder having a stem in engagement with the end of the series opposite to that in engagement with the head, and means to introduce a motive fluid between the end of the cylinder and the piston.

55 60 65 10. Apparatus for mining coal, comprising a headed rod, a series of plates adapted to move from a slanting position on the rod to a position at substantially right angles to the same, in engagement with the head of the rod, a sliding cylinder connected with the rod

and having a closed end, a piston in the cylinder having a stem around the rod and in engagement with the end of the series opposite to that in engagement with the head, and means to introduce a motive fluid between the end of the cylinder and the piston.

70

11. Apparatus for mining coal, comprising a rod, a series of slotted plates adapted to move along the rod from a slanting position on the rod to a position at substantially right angles to the same, and means to effect said movement of the units.

75

12. Apparatus for mining coal comprising a series of loose units adapted to enter into a bore of a coal formation in a slanting position, and means to effect movement of the units toward or to an erect position lengthwise of the axis of the bore, whereby to exert a lateral disruption force upon the wall of the bore.

80

13. Apparatus for mining coal comprising a series of contacting plates adapted to enter into a bore of a coal formation in a slanting position, and means to effect a movement of the plates to or toward an erect position whereby to exert a lateral disruptive force upon the wall of the bore.

85

14. Apparatus for mining coal comprising a series of unconnected and contacting units adapted to enter into a bore of a coal formation in a slanting position, and means to effect a movement of the units toward or to an erect position, whereby to exert a lateral disruptive force upon the wall of the bore.

90

15. Apparatus for mining coal comprising a series of contacting plates adapted to enter into a bore of a coal formation in a slanting position, and means to exert pressure upon an end of the series whereby to compel the plates to move conjointly through an angle toward or to an erect position.

100

16. Apparatus for mining coal comprising a series of contacting plates adapted to enter into a bore of a coal formation in a slanting position, and means to exert pressure upon the ends of the series whereby to compel the plates to move conjointly through an angle toward or to an erect position.

110

17. Apparatus for mining coal comprising a series of contacting plates adapted to enter into a bore of a coal formation in a slanting position, and means for causing said plates to move conjointly through an angle to or toward an erect position and to move them bodily lengthwise of the bore.

115

18. Apparatus for mining coal, comprising a rigid element adapted to engage in a slanting position, at opposite sides of a bore in a coal formation, and means to effect an angular movement of the element whereby to exert a lateral disruptive force upon said sides of the bore.

120

19. Apparatus for mining coal, comprising a rigid element adapted to engage in a slanting position, at opposite sides of a bore in a

125

130

coal formation, and means to effect an angular movement of the element, by pressure applied simultaneously at opposite sides thereof, whereby to exert a lateral disruptive force upon the sides of the bore engaged by the element.

20. Apparatus for mining coal, comprising a rigid element adapted to engage in a slanting position, at opposite sides of a bore in a coal formation, means to effect an angular movement of the element whereby to exert a lateral disruptive force upon said sides of the bore, and means for guiding the element in its said movement.

15 In testimony whereof I have affixed my signature.

FRED S. CALDWELL.
